Primary Examiner — Clare E Heflin*(74) Attorney, Agent, or Firm* — Workman Nydegger(57) **CLAIM**

The ornamental design for a Y-shaped light fixture, as shown and described.

DESCRIPTION

FIG. 1 is a bottom, front, right perspective view of a Y-shaped light fixture showing my new design;

FIG. 2 is a left side elevational view of the Y-shaped light fixture thereof;

FIG. 3 is a right side elevational view of the Y-shaped light fixture thereof;

FIG. 4 is a front elevational view of the Y-shaped light fixture thereof;

FIG. 5 is a rear elevational view of the Y-shaped light fixture thereof;

FIG. 6 is a top plan view of the Y-shaped light fixture thereof, and,

FIG. 7 is a bottom plan view of the Y-shaped light fixture thereof.

The broken away symbols in the drawings indicate that the appearance of any portion of the article between the break lines forms no part of the claimed design. Dashed lines show environment in the drawings are included for illustrative purposes only and form no part of the claimed design.
